UNITED STATES PATENT OFFICE.

HERBERT E. BRIDGWATER, OF DERBY, CONNECTICUT, ASSIGNOR, BY MESNE ASSIGNMENTS, TO SECOR TYPEWRITER COMPANY, OF DERBY, CONNECTICUT, A CORPORATION OF CONNECTICUT.

TYPE-WRITING MACHINE.

1,023,805.

Specification of Letters Patent. Patented Apr. 23, 1912.

Application filed January 26, 1909. Serial No. 474,348.

To all whom it may concern:

Be it known that I, HERBERT EDMUND BRIDGWATER, a citizen of the United States, residing at Derby, in the county of New Haven and State of Connecticut, have invented certain new and useful Improvements in Type-Writing Machines, of which the following is a specification.

My invention relates to certain improvements in that class of typewriting machines known as "front-strike" machines and more particularly to the construction in such machines of those portions comprising the adjustable fulcrum support and segmental guiding of the type-bars.

In typewriting machines of the class referred to, the full complement of type-bars is generally restricted within a segmental curved or arch-shaped support, the angular extent of which is less than half a circle. The subdivisions of this angle by the usual number of type-bar bearings arranged side by side, in substantially a circular arc with its center at or near the printing point, brings the type-bar heels or pivotal ends close together, confining within narrow limits any device for providing type-bars so arranged with adjustable fulcrum support and radially guiding means. On this account, it has been customary to employ an integral segment of the desired radius, and by means of saws cut closely adjoining radial slots for the reception of the type-bars as guiding means, and then to provide an annular groove intersecting these slots in which a curved rod is held as a fulcrum common to all the bars, but which provides no independent or individual adjustment of the type-bars. The subdivisions of the segment between the slots are connected only at one end to their support and it is not unusual for these divisions to warp or spring, altering the dimensions of the adjoining slots and thus make the fitting of the type-bars therein an expensive operation. Also, the removal of a type-bar from such a segment is not readily accomplished, necessitating as it does the withdrawal of the fulcrum rod from out adjoining bars on one side, unless the bar is simply suspended on that rod by an open hook, the use of which is objectionable. In this class of construction where no independent adjustment of

the bars is possible it becomes necessary to distort the bar between the type-faces and 55 fulcrum bearing to effect changes in dimensions within the bar for alining operations.

The object of my invention is first: to provide a segmental guide-support for a set of type-bars which is preferably integral in character and of such form as to avoid the springing of its radial subdivisions by the operation of slotting by forming the part to be slotted so as to provide a slot of ample guiding capacity and at the 60 same time require the removal of a comparatively small amount of metal and leave the radial subdivisions in integral connection preferably at both ends with the segment; secondly to provide a movable hanger 70 or individual fulcrum support for each type-bar individually having its point of attachment on an abutment disposed in such a plane as will permit of an independent adjustment of each type-bar fulcrum point 75 radially in a line toward or from the writing point without disturbing any of the other bars in their several individual adjustments.

To the above and other ends which will 80 hereinafter appear, my invention consists of the features of construction, arrangement of parts and combinations and devices set forth in the following specification, illustrated in the accompanying drawings 85 and particularly pointed out in the appended claims.

I have shown my invention in the present instance in its application to a front-strike machine, though it should be understood that the construction therein disclosed may be varied without departing from my device as claimed and may be readily employed on various styles of typewriting machines. 95

In the drawings, in which similar reference characters indicate corresponding parts in all the views, I have shown only so much of a typewriting machine as is necessary for the illustration of my invention. 100

Figure 1 shows the front elevation of the carriage and segment supporting bridge of the typewriter. Fig. 2 shows a sectional view of Fig. 1 at X, X to which is added the side elevation of a key-lever and its 105 connections to a type-bar which is here dis-

closed in printing position. Fig. 3 is a fragmental portion of Fig. 2 showing the greater portion of a type-bar in normal position. Fig. 4 is an underneath plan view 5 of the bridge and segment of Fig. 1. Fig. 5 is a fragmentary enlarged view of the rear elevation of the segment comprising that sectional portion forward of the line Y, Y, Fig. 2. Fig. 6 is a plan view of one 10 of the individual hangers with its type-bar journal end and an associated type-bar in section on line Z, Z, Fig. 3. Fig. 7 is a view showing a plane development of the segment on right line A, A of Fig. 2, and the 15 intersecting arc line B, B of Fig. 1, showing the arrangement of the type-bars in their relative normal position. Fig. 8 shows the side elevation of a type-bar head in printing position in connection with a modified 20 form of type-bar guide. Fig. 9 shows a front elevation of the type-bar guide illustrated in Fig. 8. Fig. 10 shows a sectional view of a modified form of my type-bar segment. Fig. 11 shows a sectional view of 25 a further modification in the form of my type-bar segment. Fig. 12 shows a sectional view of a form of my type-bar segment in which the guide member is divided, and Fig. 13 shows a sectional view of a 30 modification of my type-bar segment adapted for use in rear-pull front-strike type-writers.

The frame of the machine (not shown) supports a bridge 1 shown in Fig. 1 in front 35 elevation. The upper edge of this bridge is grooved as a guide way for the running support of the carriage, a portion of which is shown at 3, Fig. 1. This carriage supports the platen 4 for longitudinal axial move- 40 ment across the machine during the writing operation. This bridge is shown in section in Fig. 2 with the platen 4 in the position which it is carried above the bridge. From the front of this bridge 1 projects the seg- 45 mental portion 5 which, as is shown in Figs. 1 and 4, has its axis in the center of the machine and at a point just below the writing point at 6. It opens upwardly as a segment toward the upper edge of the bridge 50 1 and is in vertical relation to the front side of the platen 4. This portion of the bridge 1 will hereafter be referred to as the type-bar segment. This type-bar segment is preferably cast solid as one piece with the 55 bridge 1 on which it forms, as viewed from the front, an annular flange, but being cored out in the casting as a hollow member it forms, as viewed from the rear, a segmental recess 7, see Fig. 3. The axis of this seg- 60 mental recess is at all points uniform from the axial point 6. The arch-formed wall of this segmental recess is slotted radially as shown in Fig. 1 to a depth or extent shown in Figs. 2 and 3, to provide the guide mem- 65 bers 8 with the slots 9 for reception of the

type-bars. In thus slotting this type-bar segment it is converted into a series of arches or arch-like divisions with their faces in parallel radial alignment with the faces of adjoining arches, each archlike division 70 being attached at its extreme ends to the bridge 1 of which it forms an integral part and which effectively maintains them in fixed relative position. The arch-like form or outline of the divisions of the segment in 75 their upper portion between the axis of the type-bars and the printing point, extend tangentially to where they unite with the main body of the segment as is seen from Figs. 2 and 3. By employing the described 80 construction, I secure a type-bar heel guide bearing of relatively large effective proportions by the removal of a comparatively small amount of metal during the slotting operation, while the intervening divisions 85 are securely held against warping, springing or other displacement which would impair the dimensions of the adjoining slots. The type-bars 10 are pivotally fulcrumed on 90 individual hangers 11 which are attached to and supported by the annular abutment 12 which is disposed in a plane parallel with the axis of the recess 7 which it adjoins as a part of the bridge 1. The hangers 11 are fixedly attached to the segmental abutment 95 12 by the screws 13. The hangers 11 are shown in detail in Figs. 2, 3, 5 and 6. They are preferably in the general form of a right angle comprising a bearing arm and an attaching arm. Each of these arms is flat- 100 tened, one is slotted as at 13^a for the reception of its attaching screw so as to permit of adjustment in a direction parallel to its axis, and laterally under the head of the screw. The other arm is thinned to dimensions less than one half of the axial distance 105 between the type-bars at their fulcrum ends in their position in the segment and carries a boss or pivot stud 14, on one side of its extreme end, the length of which is equal to 110 the thickness of a type-bar at its journal end. The slotted arms of these hangers rest upon the abutment 12 in such position as to allow the bearing arms to project forwardly 115 into the recess 7 bringing the axis of the bearings 14 generally concentric with the arched wall of the hollow type-bar segment. The type-bars 10 are fulcrumed on the studs or bearings 14 in this position as shown in Fig. 2. To mount or insert a type-bar, a 120 hanger 11 is loosened by slackening its attaching screw 13 and then swung thereon to one side against an adjoining type-bar heel (if present) thereby carrying its pivot stud 14 out of line with the slot to which it is oppo- 125 site, as clearly shown in the right hand hanger in Fig. 5. The type-bar to be mounted or inserted has its heel end entered through the slot thus cleared by the swing- 130 ing aside of the hanger and the fulcrum hole

therein is adjusted to find the stud on said hanger. The hanger is then swung to position engaging the stud 14 in the fulcrum hole 15 as shown in Fig. 6. The walls of the slot 9 provide a lateral support for the type-bar in its oscillations on the bearing 14, while permitting of any necessary movement of the bar in its plane of oscillation that may be due to a movement of the hanger 11 in a similar plane. By an inspection of Figs. 1 and 2, a type-bar 10 is shown in printing position with a type-guide pin 16 engaging a type-bar guide 17, which consists of a hardened bushing mounted in the plate 17^a which is attached to the bridge 1 by the screws 17^b in such position that the guide 17 coincides with the axis of the radial slots 9 shown at 6, Fig. 1. Each type-bar carries a pin 16 to which the position of the type 18 is previously gaged in its attachment to the bar. A type-bar is engaged with a loosened hanger as described and is then brought to the position as shown in Fig. 2 with its pin in the type-bar guide, then the screw 13 of the hanger 11 is tightened which secures the hanger and bar in the proper radial adjustment to bring the pin 16 into engagement with the guide 17 at each printing operation. To remove a type-bar it is only necessary to loosen its hanger screw 13, swing the hanger to one side as previously described, when the bar may be withdrawn from its slot without disturbing any of the adjoining bars.

Ordinarily the type-bars at their heel portion will be of such dimensions in thickness as to fill the slots with a running fit, so that stud 14 will serve only as a fulcrum for the type-bar in its oscillations thereon. If as the result of long continued use, the bars and slots become worn so that in effect the slot becomes too wide to guide the bar steadily, it will only be necessary to carry the bearing arm of the hanger 11 toward the bar in a line parallel with the axis of its bearing until the type-bar heel is embraced between the opposing wall of the slot and the face of the bearing arm portion of the hanger, securing the hanger in this position as before by its screw 13. Thus the type-bar will again with certainty bring its alining pin into engagement with the type-bar guide at its printing operations.

The printing operation is performed by depressing the key-lever 19 fulcrumed on the bar 20 supported in the main frame of the machine. The key-lever 19 is operated by the finger-key 21 and its movement is transmitted to the type-bar 10 at a point 22 on its short arm 23 by the stirrup-link 24, the bell-crank 25 and the draw-bar 26. The type end of the bar 10, when in normal position, as shown in Fig. 3, rests on the pad 27, Fig. 2. Retracting springs 28 and 29 are

provided for the return of the several parts to their normal position after each writing operation.

In Figs. 8 and 9, I show a modified form of type-bar guide. The type-bars 10 enter between the forwardly projecting jaws 30 of the slotted arm 31 which is an extension of the plate 32 which may be attached to the bridge 1 by the screws 33, with the upper edge of the jaws 30 occupying a horizontal plane intersecting the axis of the type-bar guide 17 as shown in Fig. 2. The type-bars are provided with an extension 34 just below the type 18, this extension entering and co-operating with the type-bar guide. The heel portion of these type-bars would be the same as hereinbefore described. When a type-bar guide of this form is employed in connection with my improved segment and hanger, the types 18 are attached to the bars 10 in as uniform relation as possible to their fulcrum points. Final and close adjustment of the types in relation to the writing line can then be readily effected by the radially movable hangers 11 by means of which any type-bar may be shifted radially endwise toward or from the writing point independently of the type-bar segment in order to cause it to bring its type to the proper position in its printing operation.

In Fig. 7 is shown a sectional plan view of my type-bar segment in which the arc B, B of Fig. 1 is projected as a right line. Type-bars 10 are shown in plan view here in the normal position as shown in Fig. 3, mounted upon their hangers 11 in attachment with abutment 12. For the purpose of this illustration three groups of a part of the bars are shown, the types 18 being omitted from one of the groups as being duplicates only of the opposite group on which the type 18 are displayed. On these type bars are shown the type-guide pins 16 which are shown in Figs. 1 and 2 as entering the type-bar guide 17 as the point at which all the type-bars intersect at the extreme end of their radial length. Beyond this point the bars extend in a direction at an angle to the plane of oscillation of the bar in a direction which, when the type-bar is in printing position, is cross-wise of the platen or at right angles to the line of writing. The extent of this angular bend, which takes place at the axis of the guide pin 16, increases from the center of the segment to its ends, near which ends the angle is so great as to materially reduce the space between the types 18 when in their normal position. The effect of this condition would be to cause the type to collide or restrict the width of the characters that may be used on them. To obviate this effect, I carry the fulcrum bearings of a number of bars at each end of the platen gradually increasing distances rearwardly in a line parallel with the radial

slots 9 and at right angles to the abutment 12, to such an extent as to provide ample working room for the type 18 when in their normal position. This I accomplish, as shown in Fig. 7, by successively shortening the bearing arms of the hangers 11, which are near the ends of the segment, so that the axes of their fulcrum journals are in offset axial relation and progressively closer to the plane of the abutment 12. This I am enabled to do very readily in connection with my integral type-bar segment on account of the individual hangers that I employ as a part of my device, by reason of the independent character of the hanger which carries the type-bar as a fulcrum support therefore in line with its guiding slot in the integral segment.

The type-bars herein referred to are preferably of equal length, although my invention is not limited thereto, also the features of integral construction particularly alluded to in the preceding specification may be modified without departing from my invention.

In Figs. 10 to 13 inclusive, I have shown modified forms of the slotted segmental recess, the slotted faces of which form the radial guiding surfaces of large extent for the type-bar heels. In Fig. 10 the form of segmental recess is generally arch-shaped or circular in cross section but open on its upper side toward the front of the segment.

In Fig. 11 another modified form is shown in which the segmental recess is also generally arch-shaped in cross section but is open at the lower portion toward the front of the segment and the arch is of somewhat less extent than that form shown in Fig. 10.

In Fig. 12 the slotted segmental recess is shown as open toward the front of the machine thus presenting in cross section separate slots or slot faces 9 on opposite sides of the pivot stud.

In Fig. 13 the slotted segmental recess is angular in cross section presenting an angular slot face or radial guide for the type-bars.

In all of the modifications of the form of slotted recess shown in the drawings, the same principle of providing a radial guiding slot having a large guiding capacity or surface is exhibited, the form of recess in cross section being such that the type-bar is guided in all of its positions or points of travel from its position of rest as indicated in Figs. 3 and 10 to 13 inclusive, to its printing position indicated in Fig. 2; so that the type-bars are constantly guided through the full extent of their movement.

By the construction shown and described I have provided a segmental pivotal support and radial guide for the type-bars of typewriting machines, particularly of the style referred to and known as the "front-

strike" or "visible" writing machine, in which the bars are provided with ample lateral or radial guiding surfaces and with individually and independently adjustable pivot supports or bearings, and in which a full set of type bars are mounted side by side in a single series. By reason of the extended lateral guiding surfaces provided in combination with the small lateral extent or space occupied by each bar, I am enabled to accommodate a full set of bars in a single segmental arrangement or series and at the same time provide against lateral deflection of the bars in all positions in their paths of movement.

It will be understood that the precise details of the invention shown and described, may be varied by those skilled in the art without departing from the invention or sacrificing the principle or advantages thereof.

What I claim is:

1. In a typewriting machine, the combination of a series of segmentally arranged type-bars, radial heel-guides therefor and individual type-bar fulcrum supports adjustable independently interiorly of said guiding means and mounted exterior thereto.

2. In a typewriting machine, the combination of a series of segmentally arranged type-bars, radial heel-guides therefor partially inclosing an axial space and individual detachable type-bar fulcrum supports adjustable independently within said space and having their point of attachment exterior thereto.

3. In a typewriting machine, the combination of a series of segmentally arranged type-bars, radial heel-guides therefor providing a partially inclosed space and individual detachable type-bar fulcrum supports attached exteriorly of said space and extending thereinto.

4. In a typewriting machine, the combination of a series of segmentally arranged type-bars, arched radial guiding means embracing the heel portions of said bars, pivotal supports for said bars comprising individual hangers independently mounted exteriorly of said guiding means and extending into axial relation therewith.

5. In a typewriting machine, the combination of a series of segmentally arranged type-bars, arched radial guiding means embracing the heel portions of said bars, individual detachable pivotal supports for said type-bars comprising hangers mounted exteriorly of said guiding means and extending into and in adjustable axial relation thereto.

6. In a typewriting machine, the combination of a series of segmentally arranged pivotally supported type-bars, radial guiding means for said type-bars comprising a suitably slotted arched member embracing a channel and individual independently ad-

- justable type-bar hangers detachably mounted adjacent to said channel and projecting thereinto and in axial relation to the pivotal axis of said type-bars.
- 5 7. In a typewriting machine, the combination of a series of oscillating type-bars, a corresponding series of radial heel-guides therefor comprising an integral segmental member having an arched section, said member radially slotted through the arched section thereof and pivotal supports for said type-bars detachably mounted adjacent to and extending into said arched section and independently adjustable radially and in a line with said slots. 70
- 10 8. In a typewriting machine, the combination of a series of oscillating type-bars, a corresponding series of radial heel-guides therefor comprising an integral member adjacent to the axis of oscillation of said type-bars and radially slotted in planes intersecting said axis, and individual pivotal supports for said type-bars extending from the axial region thereof to points of attachment 80 on said integral member and independently adjustable in relation thereto.
- 15 9. In a typewriting machine, the combination of a series of fulcrumed oscillating type-bars constantly embraced at their heel portions and adjacent to their axis of oscillation by a corresponding series of radial guide members and independently adjustable hangers for said type-bars detachably mounted exterior thereto, and extending as 85 a fulcrum support into axial relation to said guide members.
- 20 10. In a typewriting machine, the combination of a full set of type-bars mounted as a single series in the machine, a corresponding series of integrally supported segmentally arranged radial guiding members for said bars, said guiding members extending circumferentially about the pivots of said type-bars, and individually mounted pivotal 90 supports for said bars, said supports mounted exterior to the guiding members and extending within the same.
- 25 11. In a typewriting machine, the combination of a series of type bars pivotally supported to swing in radial planes to a common printing point, a corresponding integral series of radial guide members for said bars, said guide members extending about the pivots of said bars, the extent of said 95 guide members being such as to guide the bar throughout its movement from its rest position to the printing point, and individual supports for said type bar pivots, said supports mounted exterior to the guide members and extending within the same and independently adjustable with relation to the printing point. 100
- 30 12. In a typewriting machine, the combination of a series of type bars pivotally supported to swing in radial planes to a common printing point, a corresponding integral series of radial guide members for said bars, said guide members extending about the pivots of said bars, the extent of said 105 guide members being such as to guide the bar throughout its movement from its rest position to the printing point, and individual supports for said type bar pivots, said supports mounted exterior to the guide members and extending within the same and independently adjustable with relation to the printing point. 110
- 35 13. In a typewriting machine, the combination of a series of type bars pivotally supported to swing in radial planes to a common printing point, a corresponding integral series of radial guide members for said bars, said guide members extending about the pivots of said bars, the extent of said 115 guide members being such as to guide the bar throughout its movement from its rest position to the printing point, and individual supports for said type bar pivots, said supports mounted exterior to the guide members and extending within the same and independently adjustable with relation to the printing point. 120
- 40 14. In a typewriting machine, the combination of a series of type-bars pivotally supported to print at a common point, a series of radial guide members therefor extending in circumferential relation to the pivots of said type-bars and intermediate 125 said pivots and the printing point, and adjustable detachable supports for said pivots mounted exteriorly of said guide members and extending to a position coincident to the axis of said pivots, said supports adjustable independently of said guide members.
- 45 15. In a typewriting machine, the combination of a full set of segmentally arranged type-bars pivotally mounted in a single series to print at a common point, a corresponding series of radial guide members for said bars, said guide members extending about the pivots of said bars on opposite sides thereof with respect to the printing point and having that portion thereof between said pivot and the printing point tangential of the pivot, and supports for said pivots mounted exterior to said guides and extending within the same to a position coincident with the pivotal axis of the bars. 130
- 50 16. In a typewriting machine, the combination of a series of type-bars pivotally supported near the ends of said bars to print at a common point; a series of radial guide members for said bars extending about said pivots and having the portion thereof between said pivots and the printing point tangential to said pivots, and independently adjustable detachable supports for said type-bar pivots mounted without said guide members and extending within the same to a position coincident with the pivotal axis of the bars.
- 55 17. In a typewriting machine, the combination of a series of type bars pivotally supported to swing in radial planes to a common printing point, a corresponding integral series of radial guide members for said bars, said guide members extending about the pivots of said bars, the extent of said 135 guide members being such as to guide the bar throughout its movement from its rest position to the printing point, and individual supports for said type bar pivots, said supports mounted exterior to the guide members and extending within the same and independently adjustable with relation to the printing point.

nation of a series of type-bars pivotally supported to print at a common point, a series of radial guide members therefor constantly embracing said type-bars at their heel portions concentrically adjacent to the pivots of said type-bars, supports for said pivots comprising independently adjustable detachable hangers, a supporting abutment for said hangers exterior of said guide members, said hangers having attachment on said abutment and extending to a position coincident to the axis of said pivots within said guiding means.

18. In a typewriting machine, the combination of a series of radially guided segmentally arranged type-bars, an individual hanger for each type-bar, a segmental support for said hangers having a radially slotted guide member integral therewith, and means for independently adjusting said hangers in a plane parallel to the walls of said slots.

19. In a typewriting machine, the combination of a series of radially guided segmentally arranged type-bars, an individual hanger for each type-bar, a segmental support therefor comprising an abutment and an arched portion, radial guide slots cut in said arched portion, type-bars radially guided intermediate the walls of said slots with their hangers having attachment on said abutment and extending interiorly of said arched portion, and maintaining said bars in operative relation to said guiding means.

20. In a typewriting machine, the combination of a radially slotted type-bar segment, type-bars pivotally mounted to be operatively embraced intermediate the walls of said radial slots and adjustable supports for said pivots mounted independently of said slots, and means for adjusting said supports longitudinally of the axis of their corresponding type-bar pivots.

21. In a typewriting machine, the combination of a series of type-bars, a recessed integral radially slotted segment in which said type-bars are pivotally mounted, detachable and independently mounted hangers carrying the pivots of said type-bars, said hangers extending within the recess of said segment intermediate the type-bars at their pivotal points.

22. In a typewriting machine, the combination of a series of pivotally mounted segmentally arranged type-bars a segment therefor comprising a radially slotted recessed portion, and an abutment portion adjacent to said recessed portion, type-bars extending at their heel portions interiorly of said recessed portion, and independent hangers mounted on said abutment and adjustable thereon in lines parallel with said radial slots and the axis of said pivots, said hangers pivotally supporting said type-bars.

23. In a typewriting machine, the combination of a series of segmentally arranged pivotally mounted type-bars, a segment therefor comprising a recessed member and an adjacent abutment member, radial guide slots for said type-bars intersecting said recessed member, independently adjustable individual supports for said type-bar pivots comprising a slotted attaching member and a bearing member having a pivot stud thereon, said type-bars being retained on said stud by an opposing wall of its corresponding guide slot.

24. In a typewriting machine, the combination of a series of segmentally arranged pivotally mounted type-bars, a segment therefor comprising a recessed member and an adjacent abutment member, radial guide slots for said type-bars intersecting said recessed member, independently adjustable individual supports for said type-bar pivots comprising a slotted attaching member and a bearing member having a lateral bearing face and a pivot stud thereon, said supports detachably mounted on said abutment to embrace a type-bar in guided relation between said bearing member and an opposing wall of its corresponding guide slot in said segment.

25. In a typewriting machine, a type-bar hanger comprising a slotted attaching member and a bearing member as an extension thereof, a pivot stud on one side of the bearing member and uniform in diameter throughout its length, said length being equal to the thickness of a type-bar.

26. In a typewriting machine, a type-bar hanger comprising a slotted attaching member and a bearing member as an extension thereof, a pivot stud on one side of the bearing member, said bearing member being thinned adjacent said stud to enter between closely adjoining type-bars.

27. In a typewriting machine, the combination of a series of type-bars radially guided at their heel portions by a slotted segment, a type-bar hanger therefor comprising a slotted attaching member and a bearing member as an extension thereof, said bearing member carrying a pivot stud on one side, the bearing member and stud being axially and radially removable from between said type-bar heels.

28. In a typewriting machine, the combination of a series of segmentally arranged type-bars embraced at their heel portions between the walls of radial guide slots, and individual detachable pivotal hangers for said type-bars comprising a slotted attaching member and a bearing member as an extension thereof, a pivot stud on said bearing member axially offset with relation to the pivot stud of an adjoining hanger.

29. In a typewriting machine, the combination of a full set of type-bars segmentally

- supported in a single series, a corresponding series of radial heel guides for said type bars, a corresponding series of individual detachable hangers pivotally supporting 5 said type-bars, the hangers toward the ends of the segment carrying the type-bar pivots progressively nearer the base or rear of the segment to provide a nesting of the offset type ends of the bars in normal position.
- 10 30. In a front strike typewriter, the combination of a series of type-bars segmentally arranged and pivotally supported to strike upwardly and rearwardly to print at a common point, a segment for said type-bars 15 comprising a radially slotted member and an abutment adjacent thereto, individual pivotal supports for said type-bars mounted on said abutment and pivotally supporting type-bars near the ends of said segment 20 progressively nearer the plane of said abutment.
31. In a front-strike typewriter, the combination of a series of type-bars segmentally arranged and pivotally supported to strike 25 upwardly and rearwardly to print at a common point, a segment for said type-bars comprising a radially slotted member and an adjacent abutment member, individual pivotal supports for said type-bars independently mounted on said abutment and pivotally supporting type-bars near the ends of said segment independently and progressively nearer the plane of said abutment.
32. In a typewriting machine, the combination of a full set of pivotally mounted type-bars segmentally arranged in a single series, a segmental support for said type-bars, said support recessed to form a segmental channel to accommodate the type- 35 bar pivots, the walls of said channel being radially slotted to form heel guides for said type-bars, a series of independently mounted individual hangers for said type-bars extending at their pivot ends within said
- channel, the hangers toward the ends of the 45 segment extending progressively diminishing distances within said channel.
33. In a front strike typewriter, the combination of a series of type-bars segmentally arranged and pivotally supported to strike 50 upwardly and rearwardly to print at a common point, a segment for said type-bars comprising a radially slotted arched member, and an abutment adjacent thereto, type-bars embraced at their heel-portions between the walls of said slots and longitudinally adjustable therein, pivotal supports for said type-bars mounted on said abutment and projecting at the ends of said abutment forwardly progressively diminishing 55 distances interiorly of said arched member, and maintaining their pivots in off-set axial relation to each other.
34. In a typewriting machine, means for independently and adjustably mounting the 60 type-bars, said means comprising a support for the type-bars, a recess or channel formed in said support and extending concentrically with the printing point, the walls of said recess or channel extending about the pivots 65 of the type-bars on opposite sides thereof with respect to the printing point, the walls of said channel or recess slotted radially with respect to the printing point to provide radial guides for the type-bar heels, 70 and individual and separately mounted adjustable hangers for the type-bars, said hangers secured on said segment at a point exterior of said channel or recess with their pivot ends extending within said channel 75 or recess and pivotally engaging respective type-bars extending within said recess or channel through said slots.
